FINELY DIVIDED FUEL BURNER

George P. Jackson, Flushing, N. Y., assignor to
International Combustion Engineering Corporation,
New York, N. Y., a corporation of Delaware

Application July 19, 1928. Serial No. 293,807

5 Claims. (Cl. 110—28)

This invention relates to improvements in finely divided fuel burning, and especially to burners adapted for use in furnaces which are to be fired with pulverized coal by the tangential method of firing, i. e., by introducing the fuel at the corners of the combustion chamber in directions so that the fuel and flame streams are tangent to an imaginary circle, the axis of which lies substantially in the axial center line of the combustion chamber.

One of the primary objects of my invention is the provision of a burner having a plurality of fuel nozzles in which the nozzles may be independently removed and inserted without necessitating shutting down the furnace in which they are employed.

Another object of my invention is the provision of a burner adapted to deliver the fuel in thin horizontally disposed sheets.

Still another object resides in admitting fuel and air into a combustion chamber at the corners thereof in directions tangent to an imaginary circle having a vertical axis and in substantially horizontally disposed layers of air and fuel alternating vertically.

A further object is to provide a burner which may be controlled so as to either produce or reduce slagging.

How the foregoing, together with such other objects and advantages as may hereinafter appear, or are incident to my invention are realized, is illustrated in preferred form in the accompanying drawings, wherein—

Fig. 1 is a fragmentary vertical section of a portion of a furnace showing my improved burner applied thereto.

Fig. 2 is a fragmentary plan section taken on the line 2—2 of Fig. 1, with the burner appearing in full view.

Fig. 3 is a diagrammatic plan view illustrating the arrangement of the burners for tangential firing.

Fig. 4 is an enlarged elevational view of my improved burner with the upper and lower right hand portion and the central portion of the air casing broken out and appearing in section to clearly show the interior arrangement of the burner, and also showing a portion of each of the fuel nozzles in section as well as the air deflector members which are detachably secured to the end portions of the nozzles.

Fig. 5 is a plan section of the burner taken substantially on the line 5—5 of Fig. 4.

Referring to the drawings and more particularly to Figs. 4 and 5, the burner comprises in

general an air casing or housing A and a plurality of pulverized fuel nozzles B. The air casing is built up of a plurality of sections for convenience of manufacture, but as a whole may be considered as a single member. In this instance the casing is divided into three passages or compartments a, b and c, the intermediate passage or compartment b being considerably larger than the passages or compartments a and c.

The opening d extends for the full height of the burner casing A and is provided for the purpose of admitting air to the burner. The conduit 6 through which air is supplied is secured to the casing and communicates with the opening d. The end 7 of the casing is open.

The plurality of fuel nozzles B are located in the intermediate compartment b of the casing, and they are so arranged as to divide the compartment b of the casing into a plurality of air passages receiving air through the inlet opening d and delivering air through the open end of the casing. Stated in another way, the fuel nozzles B are spaced sufficiently apart and from the walls 8 and 9 of the casing A so as to divide the compartment b into air passages 10, 11, 12 and 13.

The fuel nozzles B are inserted into the casing A through suitable openings 14 in the end 15 thereof, and are detachably secured in place by means of bolts 16 and flanges 17. Further supports for the fuel nozzles are provided by means of the shelves 18 on the interior of the casing on which the portions 19 of the fuel nozzles rest. For convenience of manufacture I preferably form the fuel nozzles of several parts bolted or otherwise secured together.

Air deflector members or vanes 20 are detachably secured to the fuel nozzles at their discharge ends for the purpose of deflecting air from the air passages directly into the discharging fuel stream.

The outer end of each fuel nozzle is also provided with two arcuate deflectors 26 one on the top and one on the bottom of each nozzle. When the nozzles are in place these deflectors cooperate with similarly curved portions 27 of the casing proper to deflect the air entering the casing through opening d toward the discharge end of the burner.

By having the fuel nozzles detachably secured in the casing A I am enabled to remove them independently of one another should it be desired to change the shape and contour of the air deflectors 20, or for cleaning purposes, inspection, or the like, and as this would not involve removing the entire burner, such changes may be made.

without necessitating a shut down of the installation.

I have also provided deflector members or plates 21 for the air passages, which members are adjustably secured to the casing A as by means of movable wedges 22 and clamping bolts 23.

Dampers 24, controllable in any suitable manner, are provided for controlling the admission of air to the air passages.

19 Referring now to Figs. 1, 2 and 3 I have there-
in illustrated the application of my improved
20 burner to a furnace C having its walls lined with
boiler tubes 25. The burners are located at the
corners and are so disposed as to deliver their
18 streams in a direction tangent to an imaginary
cylinder having its axis extending substantially
vertical as illustrated in Fig. 3. Thus the entire
furnace chamber is effectively utilized and the
impingement of one coal stream upon another
20 produces most effective rapid mixing and con-
sequently rapid and violent combustion and high
temperatures.

It is pointed out that the fuel nozzles and air
23 passages are of considerable length which per-
mits of proper directioning of the coal and air
streams. The fuel nozzles are transversely elong-
ated and have their long axes extending hori-
zontally so that the fuel is delivered in thin
horizontally disposed sheets.

30 The coal and air enters in horizontally dis-
posed layers which alternate, vertically, in a
manner causing the coal stream to spread out
and thoroughly and quickly mix with the air,
and the action produced may be regulated by
35 controlling the velocity of the air relative to the
velocity of the coal.

In addition to the air passages 10, 11, 12 and
13 which deliver air immediately adjacent the
fuel streams, I may admit streams of air to the
40 combustion chamber through the damper controlled
air compartments a and c which form additional
air passages. With a maximum amount of air entering the lowest air compartment a, a
45 cool zone is created in the lower part of the
furnace, thereby preventing slag as this air will
absorb heat from the ash pit. Further, this air,
rising thru the products of combustion, will
expedite combustion. If it is desired to create a
50 slagging furnace, the air entering through the
compartment a is reduced, which will cause the
flame to hug the bottom of the furnace, raising
the temperature at this point and causing a flow
of slag. This will also stimulate combustion due
55 to the additional flame impingement on the slag.

55 The upper air compartment c provides air
through which the ascending solid and combustible
gases rise to find such additional oxygen as
may be required for their complete combustion.

60 I claim:—

60 1. A finely divided fuel burner comprising a
casing having an open end, means dividing the
casing into upper, lower and intermediate air pas-
sages discharging through the open end of the
65 casing, the intermediate passage being substan-
tially larger than the others, a plurality of fuel
nozzles in said intermediate passage so arranged
that they divide said intermediate passage in-
to a plurality of smaller flat, horizontal pas-
70 sage and the open end of said intermediate pas-
sage into a plurality of flat, horizontal air dis-
charge openings, and means for independently
controlling the air to said upper, lower and inter-
mediate air passages.

75 2. In a finely divided fuel burning combustion

chamber the walls of which are lined with water
tubes, burner means for admitting fuel into said
chamber at the corners thereof in a direction
tangent to an imaginary circle having a vertical
axis, the said burner means comprising a casing
having an open end in the combustion chamber,
means dividing the casing into upper, lower and
intermediate air passages discharging into the
combustion chamber through the open end of the
casing, and means dividing the intermediate pas-
sage into a plurality of flat, horizontal alternate
air and fuel passages delivering superimposed
flat, horizontal alternate sheets of fuel and air
into the combustion chamber.

3. In a finely divided fuel burning combustion
chamber the walls of which are lined with water
tubes, burner means for admitting fuel into said
chamber at the corners thereof in a direction
tangent to an imaginary circle having a vertical
axis, the said burner means comprising a casing
having an open end in the combustion chamber,
means dividing the casing into upper, lower and
intermediate air passages discharging into the
combustion chamber through the open end of the
casing, means dividing the intermediate pas-
sage into a plurality of flat, horizontal alternate
air and fuel passages delivering superimposed
flat, horizontal alternate sheets of fuel and air
into the combustion chamber, and means for in-
dependently controlling the air to said upper, 105
lower and intermediate air passages.

4. A finely divided fuel burner comprising a
casing having a closed end and an open end,
means dividing the casing into upper, lower and
intermediate air passages discharging through 110
the open end of the casing, the said casing hav-
ing nozzle openings in the intermediate passage
in the closed end thereof and having an air inlet
opening at one side adjacent said closed end, a
plurality of flat independently detachable fuel 115
nozzles in said intermediate air passage having
their discharge ends at the open end of the cas-
ing and their opposite ends in said nozzle open-
ings, the said nozzles being horizontally disposed
within the casing and vertically spaced apart to 120
divide said intermediate air passage into a plu-
rality of flat, horizontal air passages communi-
cating with the air inlet opening, the discharge
end of the intermediate air passage being thus
divided into a plurality of adjacent flat, hori- 125
zontal alternate air and fuel passages, and means
for independently regulating the flow of air
through said upper, lower and intermediate air
passages.

5. A finely divided fuel burner comprising a
casing having an open end, nozzle openings at
the opposite end and an air inlet opening at one
side adjacent said opposite end, a plurality of
flat, independently detachable fuel nozzles in said
casing having their discharge ends at the open 130
end of the casing and their opposite ends in said
nozzle openings, said nozzles being horizontally
disposed within the casing and vertically spaced
apart to divide the casing into a plurality of flat, 135
horizontal air passages communicating with the
air inlet opening, the discharge end of the burner
being thus divided into a plurality of adjacent
flat, horizontal air and fuel passages, the said
fuel nozzles having at their discharge ends de-
tachable deflectors projecting into the air pas-
sages and deflecting some of the air into the fuel
streams.

GEORGE P. JACKSON.
